(57) **CLAIM**

The ornamental design for a cosmetic brush clearing pad in combination with a tube holder, as shown and described.

DESCRIPTION

FIG. 1 is a perspective view of a cosmetic brush clearing pad in combination with a tube holder showing my new design, wherein the cosmetic brush clearing pad is hidden from view;

FIG. 2 is an elevational view comparable of FIG. 1, wherein the views from all 360° around are mirror image;

FIG. 3 is a top plan view of FIG. 1;

FIG. 4 is an additional perspective view with the closure removed from the holder base of the tube holder and with the cosmetic brush clearing pad shown inside the holder base rolled up in a coil;

FIG. 5 is a front elevational view of FIG. 4;

FIG. 6 is a right side elevational view of FIG. 4;

FIG. 7 is a left side elevational view of FIG. 4; and,

FIG. 8 is a rear elevational view of FIG. 4.

The broken lines in the drawing represent environmental subject matter that forms no part of the claimed design. In FIG. 4, the environmental broken line disclosure of the brush and additional pad form no part of the claimed design.
